UNITED STATES PATENT OFFICE.

GILBERT W. GOODRIDGE, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ELECTRIC-LAMP SOCKET.

961,605.

Specification of Letters Patent. Patented June 14, 1910.

Application filed February 10, 1910. Serial No. 543,156.

To all whom it may concern:

Be it known that I, GILBERT W. GOODRIDGE, a citizen of the United States of America, residing in the city of Bridgeport, in the county of Fairfield, in the State of Connecticut, have invented certain new and useful Improvements in Electric-Lamp Sockets, of which the following is a specification.

10 The object of my invention is to construct an incandescent electric lamp socket or the like appliance with an efficient key or switch mechanism which will give a double break, breaking both sides of the circuit simultaneously with large breaking capacity, and with the key spindle itself maintained at all times in a position at right angles to the axis of the socket and never included in the circuit, and the screw shell and center contact both being free from current when the circuit is broken.

15 In the accompanying drawings Figure 1 is a vertical section on the line 1—1, Fig. 5, of a socket embodying my improvements, the inclosing shell and cap being omitted for the sake of simplicity; Fig. 2 is a similar view, but with the key turned to the "off" position; Fig. 3 is a sectional view on the line 3—3, Fig. 5; Fig. 4 is a sectional view 20 on the line 4—4, Fig. 5; Fig. 5 is a plan view of the socket with the upper insulating block removed; Fig. 6 is a perspective view of a part; Fig. 7 is a perspective view of a modification; Fig. 8 is a perspective view of 25 another detail; Fig. 9 is a sectional view of a modified form of socket.

30 I have shown my invention as embodied in a socket in which the insulating body is made in two parts, A being the upper block and B being the lower block, which carries the lamp-receiving terminals, consisting in this case of the screw shell S and center contact C. The two blocks A and B may be conveniently secured together mechanically by 35 means of screws and binding posts, D and D¹ located in chambers on opposite sides of the insulating body, these chambers being formed by recesses in the juxtaposed faces of the two blocks A and B, Fig. 4, in the 40 manner described in the Perkins patent 626,927. In this case, however, neither binding post D, D¹ is in direct electrical connection with either of the lamp-receiving terminals. In connection with each of these 45 posts D, D¹ is a substantially horizontal

spring contact finger E, E¹ in a horizontal chamber e (e¹) in the lower block, these chambers being continuations of the chambers containing the posts D and D¹ respectively, and extending in opposite directions and near the opposite sides of the block, Fig. 5. Each spring finger E (E¹) has its inner end α bent inwardly and clamped under the lower foot of the post D (D¹), as shown in Fig. 8, so that the spring finger lies over this foot of the post and so allows the greatest possible length for the spring finger, which is itself of the curved form shown in Figs. 5 and 8. Under the free ends of these two spring fingers E, E¹ are contact plates 70 F, F¹ in the inner ends of the respective chambers e, e¹. The plate F is mechanically and electrically connected to the screw-shell S by the screw f, while the plate F¹ is mechanically and electrically connected to the 75 center contact C by the screw f¹, Fig. 3. Normally the fingers E, E¹ are held out of contact with their respective plates F, F¹ by the elasticity of the fingers, as shown in Figs. 2 and 3, and both sides of the circuit to the lamp are then broken or open. To close the circuit I provide a cross-bar in the form of an insulated plate K, which extends across from one chamber e into the other e¹, and has its ends lying over the spring fingers E and E¹, Figs. 1, 2 and 5. This plate is guided and free to have a vertical movement upon a frame J, secured to the lower block B, in the center of the insulating body. A spiral 80 spring h on the under side of the plate K tends to press the latter upward against the cam M, Figs. 2, 3 and 4, which is guided in the frame J and is mounted with the usual lost motion upon key spindle P. This latter is mounted in bearings in the frame J and is 85 provided with a suitable handle p, as usual.

The cross bar K may be variously constructed, but I prefer the form shown in Figs. 1 to 6, consisting of a metal plate k with a lower facing k¹ of vulcanized fiber or other suitable insulating material to bear upon the contact springs E, E¹.

90 In Fig. 7, I have shown the cross bar as in the form of a plate with insulated buttons at the ends. The construction may be modified in other ways provided suitable insulation is interposed to prevent a short circuit across from one contact E to the other E¹ by means of the cross bar K, whose function is essentially the mechanical one of pressing down 105 110

- these spring contacts E and E¹ into connection with the plates F and F¹ to close the circuit, as shown in Fig. 1, by the actuation of the cam M on rotating the key spindle.
- 5 On a further movement of the key spindle, the cam M will be thrown to the position Figs. 2, 3 and 4 and the circuit broken at both F and F¹ on both sides of the lamp by the upspringing of the spring fingers E and E¹.
- 10 In Fig. 9, I have illustrated in vertical section a modification in which the two horizontal spring contact fingers E and E¹ are actuated directly each by its own insulated cam N (N¹) mounted with suitable lost motion upon the key spindle P¹, and with this construction the cross bar K may be dispensed with.
- 15 With the constructions described, it will be seen that not only is there thus provided a double break, but owing to the length of the fingers E and E¹ in the long chambers e and e¹, Fig. 5, in the opposite sides of the insulating body, a large breaking capacity is secured by the distance to which the said fingers can be made to separate from the plates F and F¹. The key spindle is "dead;" that is, free from current at all times, and both the lamp-receiving terminals C and S are free from current when the key is turned to the "off" position.

I claim as my invention—

1. A key socket having an insulating body provided with lamp-receiving terminals and wire terminals, horizontal curved chambers in the body near the opposite sides thereof, stationary contacts in the chambers and substantially horizontal spring contact fingers also in the latter to make connection with said stationary contacts and means to press 35 the two spring contacts into connection with the respective stationary contacts.
2. A key socket having an insulating body provided with lamp-receiving terminals, and with binding posts in recesses at opposite 45 sides, two chambers in the body extending in opposite directions from the respective recesses, stationary contacts in connection with the said terminals and two spring contact fingers extending from said binding posts

into said chambers and means to press said contact fingers to close the circuit between the binding posts and the respective lamp terminals.

3. A key socket having an insulating body provided with lamp-receiving terminals and 55 binding posts, chambers in the body, stationary contacts in connection with said terminals and two substantially horizontal spring contact fingers having their inner ends bent inwardly and clamped under the respective posts and means to act on the contact fingers to make or break the circuit at their free ends.

4. A key socket having an insulating body provided with lamp-receiving terminals and 65 wire terminals, chambers in the body, stationary contacts in the chambers and substantially horizontal spring contact fingers to make connection with said stationary contacts and a key spindle and cam means to 70 press the two spring contacts into connection with the respective stationary contacts.

5. A key socket having an insulating body provided with lamp-receiving terminals and 75 wire terminals, stationary contacts and spring contact fingers to make connection with the latter, a cross bar to act on the contact fingers, a key spindle and cam means to act on the cross bar and insulation to prevent short circuit from one finger to the 80 other.

6. A key socket having an insulating body provided with lamp-receiving terminals and 85 wire terminals, stationary contacts and spring contact fingers to make connection with the latter, a cross bar in the form of a plate with insulation to act on both fingers, a key spindle and cam means to act on the plate, a frame and a spiral spring to act on 90 the plate, all substantially as described.

In testimony whereof I have signed my name to this specification, in the presence of two subscribing witnesses.

GILBERT W. GOODRIDGE.
